The ornamental design for a charging stand for thermometer as shown and described.

DESCRIPTION

FIG. 1 is a front, right side, perspective view of a charging stand for thermometer showing our new design;

FIG. 2 is a front view thereof; a rear view is omitted because it is mirror image of the front view;

FIG. 3 is a left side view thereof; a right side view is omitted because it is mirror image of the left side view;

FIG. 4 is a top view thereof;

FIG. 5 is a bottom view thereof; and,

FIG. 6 is a front, right side, perspective view thereof, shown in a state of use with a thermometer.

The broken lines indicate portions of the article that form no part of the claimed design: the broken lines showing of the thermometer in FIG. 6 illustrate environmental structure and form no part of the claimed design.
